UNITED STATES PATENT OFFICE

FRIEDRICH EMIL KRAUSS, OF SCHWARZENBERG, GERMANY

CENTRIFUGAL MACHINE

Application filed July 10, 1930, Serial No. 467,109, and in Germany November 8, 1929.

This invention relates to a centrifugal machine, intended especially for ununiform charges, as is the case, for instance, with linen and the like. The introduction of centrifugal washing machines into households presents great difficulties, as it is indispensably requisite not only to build these machines very strongly and able to resist the severe oscillations arising when the linen receptacle is ununiformly charged, but also to give it a separate base in order to prevent it from wandering as a consequence of said oscillations. Also the drive of the existing domestic centrifugal washing machines is very dangerous and the means therefor must be designed very carefully which entails many difficulties and corresponding costs. As charging the linen receptacle with the linen actually uniformly takes place practically never, it is practically impossible to obviate the severe oscillations, and this being so the drive must be powerful, as a part of the power is consumed by the oscillations which are transmitted from the linen receptacle to the casing or shell and the frame of the machine. The motor must be correspondingly larger, it is more expensive, and consumes more electric current.

The object of the present invention is to provide a particularly practical centrifugal machine which is completely free from the above-stated drawbacks also for small households. This machine can be operated without the least danger, it does not necessitate a separate base, but can be placed upon the ordinary floor without any separate fastening thereon, and requires for its operation only just so much power as is actually necessary for driving the centrifugal drum with the requisite number of revolutions. In this machine the centrifugal drum is suspended somewhat similar like a pendulum, that is to say, it can swing on its support, as there is provided for a lateral play on all sides between its support and the adjacent circumferential wall of the drum. Thus, if the drum is charged ununiformly, it can assume an oblique position, or adjust itself in an angle relatively to the ideal axis of oscillation. There arise, thus, either no oscillations at all, if the drum should have been charged uniformly, or only so slight ones that they can be neglected; at any rate, they are hardly perceptible and perfectly harmless. And as, finally, the casing or shell and the frame are not in the least influenced by these very small oscillations, if such ones should arise in a given case by reason of particular causes, the machine remains on its place on the floor; it does not wander.

In order to obviate a positive drive for the freely suspended drum so that it can freely follow the tendency to assume an oblique position owing to an ununiformly distributed charge, compressed air is employed as driving means for the centrifugal drum. This air might be drawn from any compressed-air source where there should exist such a one, but as this will be only very rarely the case, especially in a small household, I prefer to produce the requisite small amount of compressed air in the machine itself, the motor being united with a blower for this purpose. The compressed air constitutes a yielding driving agent which does not in the least prevent the drum from assuming an oblique position, if necessary, but that air transmits, nevertheless, a sufficient amount of power to drive the drum with the necessary number of revolutions, viz about 1100 per minute or even more. This manner of driving the drum renders the drive absolutely dangerless; it is, in fact, possible to stop the drum without any danger even while it is running with full speed. If a resistance should arise, caused, for instance, by a piece of linen that has been flung out of the drum and between the blades on which the compressed air is acting, then the drum will stop at once quite automatically, as the air can freely continue to flow and escape without any dangerous reaction upon any part, especially on the motor which is perfectly prevented from fusing or blowing from such a reason.

The invention is illustrated diagrammatically and by way of example on the accompanying drawing, in which Figure 1 is an axial section through a centrifugal machine designed according to this invention;

100

Figure 2 is a plan thereof; Figures 3 and 4 are details which will be fully dealt with hereinafter; Figure 5 is an axial section through another constructional form of the machine, showing, however, only the upper part thereof; and Figure 6 is a plan of the parts shown in Fig. 5.

On the drawing, *a* (Fig. 1) denotes the stationary casing or shell of the machine which forms at its lower end a circular gutter *a'* intended to receive the water flung out of the centrifugal drum during the operation of the same. The circumferential inner rim of said gutter may be slightly conical. From this rim is suspended the motor *d* by means of a frame *b* and arms *b'*, but between these arms and the motor is inserted a strong rubber ring *c* which is clamped fast at its outer rim, as well as its inner rim, and prevents transmission of oscillations of the motor to the frame of the machine. The motor may have a base plate of its own so that it can stand thereon if it should become necessary from any reason to disconnect it from the machine. The upwardly projecting shaft of the motor carries blades *e* which may be detachable and constitute a blower by which the compressed air necessary for driving the centrifugal drum is produced. The motor and the set of blades can be removed from the machine as a unit after the cover *h* and the drum *g* have been removed from the casing or shell *a*, and the said parts (motor and blades) may be used for ventilating purposes at some other place when the centrifugal machine is not required.

From the frame *b* extend upwardly arms *f* supporting a sleeve *f'* which is closed at its upper end and forms here a thrust bearing *f'* serving as support for a rounded pivot *g'* which is located centrally within the centrifugal drum *g* and is firmly connected with the same, or, more precisely, with the inner wall of the drum. The member forming at its lower end the pivot *g'* forms at its upper end a knob *g''* by means of which the drum can be lifted out of the shell *a* after the cover *h* has been removed. From the bottom of the drum extend downwardly blades *e'* upon which act the currents of air generated by the blades *e* so that the drum can be rotated in this way.

Owing to the drum being supported or suspended in the manner shown and described, that is to say, owing to the provision of the tubular space between the sleeve *f* and the inner wall of the drum *g*, this latter can assume an oblique position if it should have been charged ununiformly, and it can rotate quickly and uniformly also in the oblique position.

In spite of the great safety of that manner of driving several additional measures can be taken in order to increase still more that safety. Thus, for instance, the cover *h* may

be provided with a cylindrical rim *h'* which is guided in the upper portion of the shell; that is to say, the cover is guided vertically and can now be lifted a little by the pressure of the air that has been driven into the shell by the blades *e* and *e'*. At the inner face of the cover are brake blocks *m* which bear upon the inwardly curved upper part of the drum *g* when this is at rest. The drum can, thus, commence to rotate only when the pressure of the air in the shell has become high enough to lift the cover, and in order to prevent the air from escaping through the outlet orifices of the gutter *a'* these orifices are designed as siphons, as shown at *a''* in Fig. 1.

Furthermore, another brake block *i* is located just over the knob *g''* and attached to a vertical pin *i''* (Figs. 1 and 2) guided in a sleeve *h'* secured to the cover *h* in the centre thereof. On the upper end of the pin *i''* is a knob *i'*, by means of which the brake block *i* can be pressed upon the knob *g''* so as to brake thereby the centrifugal drum. The pin *i''* cannot, however, be moved directly vertically in the sleeve *h'* into its lowermost position, but it has one or two radially projecting pins *k* which engage an angular slot *k''* of the sleeve *h'*. The knob *i'* must, thus, be turned in order to move the pin *i''* down into its lowermost position.

This pin is connected with the one end of Bowden cables *k'* which extend over the cover *d* downwardly to bolts *l* which engage holes of the upper rim of the shell when they are in their coupling position. These holes are vertically oblong so that the bolts have some vertical play in it, viz., so much play that the cover can be lifted by the compressed air, viz., so much lifted that the brake blocks *m* are moved away from the drum *g*. Moving down the brake block *i* upon the knob *g''* so much that the pins *k* can enter into the slot *k''* can take place only when the drum is not in an oblique position, that is to say, when it is at rest, as generally the drum has a certain, maybe only slight, oblique position in consequence of ununiform distribution of the linen in it. When the drum is at rest and the knob *i'* is turned in

order to move the pins *k'* along in the oblique slot and to move the brake block *i* down upon the knob *g''*, the cables *k'* are wound around the pin *i''* and the bolts *l* are withdrawn from the rim of the shell so that only now the coupling members of the shell and the cover are disengaged and only now the cover can be removed from the shell.

The drum *g* may have perforated walls, as indicated by the letter of reference *g'''* so that the air can pass to the linen in the drum and assist in removing the moisture from it and in drying it. The wings *e* can, for the same purpose, be elongated upwardly so as to extend into the space between the sleeve *f* and the inner wall of the drum so

that the air propelled by said blades is driven directly into the drum from said space.

In Fig. 4 is shown that the position of the members supporting the drum can be reversed, that is to say, the rounded pin g' may be located upon the top of the sleeve f and the counter member f' may be connected with the knob g'' .

Referring now to the modification shown in Figs. 5 and 6, the cover h is in this case provided with an inwardly directed flange r touching nearly the drum g . This flange is located about in that plane in which is located also the point of contact between the supporting members f' and g' of the drum, this plane being that in which the extent of the lateral movement of the drum is the smallest, practically nearly zero. If said flange would be located at a higher or at a lower place the possibility would exist that the drum would rub at the inner edge of the said flange r , and a braking action would arise, without, however, reacting detrimentally upon the motor. The flange r divides the interior of the shell a , that is to say, the annular space between the shell and the drum, into two superposed parts n and n'' ; the shell part located at the top of the lower one n of said two spaces is bulged out, as at q (Fig. 6), and forms a spirally enlarged passage half round the shell a and the compressed air produced below the drum and entering into said lower space n passes through said passage q of the shell a in the direction indicated by the arrow in Fig. 6. At the end of the passage q is a branch n' to which is attached a hose o , the other end of which passes through an additional cover h'' into the upper part of the main cover h as well as into the centrifugal drum. That compressed air is the waste of the driving air and pushes directly upon the linen in the drum so as to assist the treatment of the same in the drum. The main cover h forms a corresponding spirally enlarging passage p , located just over the passage q and being provided with an adjustable flap p' which permits the used air to escape. When this flap is closed, the pressure of the air in the machine rises, as does, consequently, also the number of revolutions of the drum, so that the water retained in the moist linen is more quickly and thoroughly flung out; this having been accomplished, the flap p' is opened so that the air entering through the hose o is now chiefly utilized for the drying purpose.

The air may also be used for braking the drum, viz. it may be introduced into the shell through nozzles and these may be so disposed as to be turnable so that the currents of air can be conducted either in the driving direction or counter thereto, in which latter case the air will act braking; it is also possible to provide two sets of nozzles, the one being

directed and acting in the driving direction, the other counter thereto.

In the constructional form shown in Fig. 1 the direction of the air can be reversed by reversing the direction of the motor and, thus, of the blades e , when these blades will act sucking instead of blowing.

I claim:

1. A centrifugal machine, comprising an outer casing, a basket drum rotatably supported in said casing by means of a rounded pivot and a pan bearing of greater radius than said pivot giving free lateral motion to said drum, fan blades arranged on said drum, a blower arranged below and coaxially with said drum, and means for driving said blower, substantially as described.

2. A centrifugal machine, comprising an outer casing, a basket drum rotatably supported in said casing by means of a rounded pivot and a pan bearing of greater radius than said pivot giving free lateral motion to said drum, fan blades arranged on said drum, a blower arranged below and coaxially with said drum, means for driving said blower, and an electric motor connected coaxially to said blower, substantially as described.

3. A centrifugal machine, comprising an outer casing, a basket drum rotatably supported in said casing by means of a rounded pivot and a pan bearing of greater radius than said pivot giving free lateral motion to said drum, fan blades arranged on said drum, a blower arranged below and coaxially with said drum, means for driving said blower, an electric motor connected coaxially to said blower, both motor and blower suspended by means of conical sleeves on said casing, substantially as described.

4. A centrifugal machine, comprising an outer casing, a basket drum rotatably supported in said casing by means of a rounded pivot and a pan bearing of greater radius than said pivot giving free lateral motion to said drum, fan blades arranged on said drum, a blower arranged below and coaxially with said drum, means for driving said blower, an electric motor connected coaxially to said blower, and supports arranged on said motor for the bearing of said drum, substantially as described.

5. A centrifugal machine, comprising an outer casing, a basket drum rotatably supported in said casing by means of a rounded pivot and a pan bearing of greater radius than said pivot giving free lateral motion to said drum, fan blades arranged on said drum, a blower arranged below and coaxially with said drum, means for driving said blower, a cover enclosing and covering the uppermost part of said drum, and said cover being guided axially in said casing, substantially as described.

6. A centrifugal machine, comprising an outer casing, a basket drum rotatably supported in said casing by means of a rounded pivot and a pan bearing of greater radius than said pivot giving free lateral motion to said drum, fan blades arranged on said drum, a blower arranged below and coaxially with said drum, means for driving said blower, a cover enclosing and covering the uppermost part of said drum, and said cover being guided axially in said casing, and vertically arranged braking blocks on the inside of the cover, substantially as described.
7. A centrifugal machine, comprising an outer casing, a basket drum rotatably supported in said casing by means of a rounded pivot and a pan bearing of greater radius than said pivot giving free lateral motion to said drum, fan blades arranged on said drum, a blower arranged below and coaxially with said drum, means for driving said blower, a cover enclosing and covering the uppermost part of said drum, said cover being guided axially in the said casing, a spirally enlarging passage about around one half of said casing just below said cover, a flange on the lower rim of said cover and extending inside therefrom, a pipe connected to the largest part of said passage, an opening in said cover to receive the other end of said pipe, a corresponding spirally enlarging passage on said cover, and a flap on the end of this passage to open or close it, substantially as described.
8. A centrifugal machine, comprising an outer casing, a basket drum rotatably supported in said casing by means of a rounded pivot and a pan bearing of greater radius than said pivot giving free lateral motion to said drum, fan blades arranged on said drum, a blower arranged below and coaxially with said drum, means for driving said blower, an electric motor connected coaxially to said blower, a cover enclosing and covering the uppermost part of said drum, said cover being guided axially in said casing, a handle-knob on the centre of said drum, and a central brake guided in the centre of said cover against spring action and having a handle to be brought into engagement with said central brake, substantially as described.

In testimony whereof I affix my signature.

FRIEDRICH EMIL KRAUSS.
